SEPARABLE RING FASTENER

Charles H. Swenson, Plainfield, N. J., assignor to Union Carbide and Carbon Corporation, a corporation of New York

Application September 12, 1951, Serial No. 246,219

3 Claims. (Cl. 129—1)

This invention relates to a separable fastener of the ring type which is adapted for use with either separate sheets or with continuous sheets, as described in my Patent 2,537,172, dated January 9, 1951, for "File for Continuous Sheets," and has for an object to provide an improved fastener making it possible to turn the sheets as in a loose-leaf notebook with greater ease. Another object is to provide such a fastener that is less likely to tear outer sheets, particularly when no covers are provided. A further object is to provide such a fastener that may be locked in one position to keep the covers from being opened. Still another object is to provide such a fastener that may be quickly and easily attached to a stack of sheets by threading one side of the fastener through the stacked sheets, instead of the usual practice of threading a few sheets at a time onto the fastener. Yet another object is to provide a clamping device for retaining the sheets and covers closed under compression, the same being also adapted for holding the stacked sheets firmly in position with their perforations aligned during the process of threading the fastener through the stack of sheets.

Much time and expense are involved today in inserting and handling perforate sheets in a binder. The binders themselves are expensive and the fasteners require time for many sheets to be fastened.

According to this invention, an improved ring type separable fastener is provided that may be inserted and removed from almost any number of sheets and one that is less likely to tear outer sheets, in event no covers are used. These fasteners may cooperate with stiff covers to provide the new result of locking the covers against being opened.

More specifically, as illustrated, the preferred embodiment contemplates a separable spring ring type fastener having parallel straight side portions. The upper connecting portion between these side portions is provided with an upwardly inclined part and a small radius bend, enabling sheets to be raised and guided up the inclined portion to the crest of the bend and not requiring the sheet to be guided thereafter as it falls by gravity down an opposite side portion. A flange at the bottom of either or both side portions reduces the tendency for sheets to be torn when no covers are used. The overlapping ends, where separation occurs, are shaped to avoid any bulge or recess on which a sheet might catch before falling flat into the desired position. The bottom connecting portion forms substantially a right angle between the side portions, with the lower surface of this lower connecting portion flattened to give the fastener stability on a flat surface like a desk.

Referring to the drawings:

Fig. 1 is a perspective of one embodiment of this invention;

Fig. 2 is a bottom view of the device of Fig. 1 in closed position;

Fig. 3 illustrates a preferred embodiment of this invention with the fastener open;

2

Fig. 4 shows the separable fastener of this invention in use having the pages to be turned on the right side and those already turned on the left side;

Fig. 5 is a perspective detail looking at the separable portions of the fastener of Fig. 3 prior to its being closed;

Fig. 6 is an enlarged detail of the separable portions of the fastener in closed position;

Fig. 7 shows the separable fastener of this invention applied to the binder, so that the fastener will provide a locking function for the binder and its contents;

Fig. 8 is a perspective showing the device of this invention with a compression device for holding the stacked sheets with their perforations in alignment prior to insertion of the separable fasteners;

Fig. 9 shows another embodiment of this invention in which the top cover is adapted to take the place of the separate compression plate of Fig. 8;

Fig. 10 is view corresponding to Fig. 2 but in which the clamping plate covers only a small portion of a sheet at the top.

The separable fastener of this invention is provided with side portions 10 and 11, which are substantially parallel, the length of these portions depending upon the thickness of sheets that are to be held by the fastener. In other words, the fastener of this invention is preferably made in several sizes or lengths. Adjacent the upper right portion 10 is the separable part, explained more in detail herein-after, in connection with Figs. 5 and 6. The upper connecting portion 12 shown in the drawing as being curved extends between the side portions 10 and 11 slopes upwardly and rearwardly from the separable part of the fastener; a bend 13 at the apex is of much shorter radius of curvature than half the distance between the side portions 10 and 11. The lower connecting portion 14 is provided at the junction of the connecting portion and either or both of the side portions, with a flange 15 or flanges 15 and 15a. These flanges are preferably formed by upsetting some of the metal of which the fastener is composed, so that the flange will have a diameter in excess of the diameter of the standard perforations in the continuous fan folded sheets used in the business tabulating machines which sheets are to be fastened. If not formed of fastener material, the flanges may be soldered or welded in place. The purpose of these flanges is to lessen the tendency for sheets of paper at each end of the stack to be torn when contiguous the base portion 14. With such flanges, it should be no longer necessary to reinforce the paper around the perforations, as so often has to be done now.

The bottom face of the lower connecting portion 14 is flattened, as shown in Fig. 2, in order that the flat surface may have a better foundation and tend to stand upon a flat surface, such as the top of a desk or table.

In Fig. 4, the fastener is in an upright position connecting two stacks of sheets 17 and 18; those on the right designated by the numeral 17 are what remain of an original stack of sheets before the pages being turned as in turning the pages of a book fall on the stack 18. In other words, in the stack 18 are pages which have been turned over from the stack 17. In turning the pages, it is desirable to raise and guide a sheet or sheets up the side 10 of the fastener and upwardly on the inclined portion 12. When the sheet or sheets being turned have reached the apex, they may be released and fall by gravity down the side portion 11 without it being necessary for an operator to guide the page or pages being turned downwardly, as is so often necessary with the circular ring type fasteners. Stated in another way, it is only necessary for the operator to raise and guide the sheets being turned to the apex 13 and not necessary to guide these sheets downwardly. The stack of sheets shown in Fig. 4 is, for purposes of illustration, shown as

separate or individual sheets, but it will be understood that the separable fastener of this invention is also well adapted for continuous sheets, as shown and described in my prior Patent #2,537,172, dated January 9, 1951, for "File for Continuous Sheets." The finished fastener is preferably 5 of spring steel in order that the separable side portion 10 may spring away from the upper connecting portion far enough so that the open side portion 10 may be threaded through a stack of sheets having their perforations aligned.

In Figs. 5 and 6 are shown details of the separable connection in which each of the separable portions is provided with a projection 19 or 20, and corresponding recesses 22 and 23 in which these projections are received. Such projections are desirable in order that no longitudinal thrust along the side portions may tend to separate or open the fastener. For purposes of illustration, the projections 19 and 20 are shown as being rounded, but these may be of rectangular or polygonal cross section. The meeting edges of the separable portions 21 are preferably flattened and engage snugly without any substantial recess or enlarged portion being present, upon which the paper might catch in being turned. In other words, the external surface of the fastener at the separable portions is of the same general shape as elsewhere, in order to reduce the possibility of any paper catching on a bulge or ledge.

In Fig. 7, the preferred embodiment shown in Fig. 3 is illustrated as having been passed through a stack of sheets placed between upper and lower covers 24 and 25 of stiff material such as is commonly used in the trade for the covers of loose-leaf binders. The corners of these covers adjacent the perforations through which the fastener passes are rounded, as illustrated at 26, to provide a cam surface over which the fastener may be moved, causing the side portions 10 and 11 to separate slightly or be bent apart, and then, upon further movement, the side portion 11 will snap into recesses 27 and 28, shown as being provided on the upper outer edges of the covers. When a fastener is in the position shown by dotted lines in Fig. 7, the action of a fastener side portion upon the covers tends to hold the covers against being opened. In Fig. 7, with the fastener in the dotted line position, the side portion 11 is outside of the sheets being held by the covers when that portion is received in the recesses or notches 27 and 28. To open the covers and provide access to the sheets held between them, the side portions 10 and 11 are spread until the side portion 11 can move out of the notches 27 and 28 and be swung around the cam surfaces 26 into the full line position; when the covers and sheets are then adapted to be turned over, as illustrated in Fig. 4. While the notches have been shown in Fig. 7 as residing only in the covers 24 and 25, it will be understood, if no covers are used, that a stack of sheets without such covers might also be held 45 closed by the fastener, provided the notches corresponding to those numbered 27 and 28 are formed in the side edges of the sheets near the top, so that the fastener may exert a similar action upon the stack and be turned to the dotted line position shown in Fig. 7. Without such covers, the adjacent corners of the sheets should be rounded to provide cam surfaces 26.

As shown in Fig. 8, separable fasteners of the type previously described are shown as passing through a stack of sheets between covers 24a and 25a. In order to exert a clamping or compressive action upon the stack of sheets for holding them with their perforations in alignment, and to facilitate threading the fasteners through the stack of sheets, a compressive device is illustrated. This comprises base plate 29, preferably of metal, from which upstanding posts 31 and 32 may project, these having on their inner sides ratchet teeth 33 for engagement with the edges of perforations in an upper clamping plate 30 to hold the sheets and covers clamped together after the manner of a post binder, the stop clamping plate 30 being 50

pressed downward over the posts. The perforations in this plate 30 are so spaced that the posts are spread slightly, so that the teeth 33 clamp edges of the perforations in the plate 30 and hold the plate 30 pressed against the binder or stack. To release the upper plate 30, it is necessary to spread the posts 31 and 32 with the fingers, thus releasing the ratchet teeth from their engagement with the edges of the plate. A flexible portion 34 may or may not be provided in the cover 24a. One use of the compression device shown in Fig. 8 is to clamp the stack of sheets with their perforations aligned for threading the fastener through the entire stack. As illustrated in Fig. 8, for this purpose the compression device is located preferably close to the portion of the stack through which the fasteners pass, with the posts 31 and 32 outside both the covers and sheets. After the separable ring type fasteners have been engaged, the clamping device may be entirely removable or, where desired, for filing this clamping device may be moved closer to the center or lower edge of the covers and sheets remote from the edge adjacent which the separable fasteners pass. Thus, in Fig. 8, either or both the compression type fastener or the separable ring type fasteners may be used.

In Fig. 9, another embodiment of the device illustrated in Fig. 8 is shown. In this case, a lower compression plate 29b is used beneath the cover 25b, but the upper cover 24b is of stiff, wear resistant material capable of functioning both as a cover and as an upper compression plate, making a separate upper compression plate unnecessary. The posts 31b and 32b are provided with the same ratchet teeth 33b as mentioned previously and as illustrated. These posts pass through the covers but outside of the sheets held therebetween. In Fig. 9, as in Fig. 8, the fasteners exert a locking action upon the covers in addition to the clamping action of the compression device; but, since the posts in Fig. 9 are not adapted to be moved away from the separable fasteners, there is less necessity for having both clamping devices in use simultaneously. If desired, additional perforations not shown but located adjacent the opposite or lower edge of the covers may be provided, so that the compression device may also be moved to engage the covers adjacent their lower edges. In this latter event, there will be more use for a clamping device at both the top and bottom of the covers.

Unlike the usual separable fastener, that of this invention may be threaded through a thick stack of sheets and then closed, as distinguished from the somewhat usual present practice of threading one or a few sheets at a time onto the fastener, as is common with the circular ring type fastener. Locating the separable portion close to the upwardly inclined part 12 enables the fastener to be readily disengaged, somewhat after the manner of a safety pin, but, unlike the safety pin, there are no bulges or ledges against which a cover or sheet is likely to catch in being turned.

In Fig. 8, it is possible to have the equivalent of a post binder and a separable fastener ring type binder, both at the same time. In this way, with the top plate 30 of Fig. 8 close to the separable fasteners and above the flexible portion 34, then, by releasing the top plate 30 in the manner described it is possible to insert a page or pages anywhere desired by turning over the desired number of pages with the aid of the separable fasteners, as shown in Fig. 4, and, on opening the fasteners the sheet or sheets can be inserted in the desired place, yet have the sheets on each side of the newly inserted sheets still held together in order. In other words, with the device of Fig. 8, it is possible to have the equivalent of a post binder yet have such binder capable of having the sheets held by the separable fasteners during insertion of new sheets or removal of sheets wherever desired without having to remove any sheets not desired to be removed from the fasteners. Stated in another way, the device of Figs. 8 and 9 enables a post binder to be made possessing the advantages of a ring binder for loose leaves. On spread,

ing the posts the lower plate may flex enough to allow the plate 30 to be released.

In Fig. 10 is shown another embodiment enabling the advantages of a post and a separable ring type binder to be present simultaneously. The clamping plate 30c is shaped to extend between the perforations in the paper and the top edge, i. e. between the side 10 of each fastener and the top edge of covers 24c and 25c. The base plate 29c may be recessed to receive the bottom connecting portion 14 of each fastener or if not so recessed can pass across below or outside such connecting portions 14 of the fasteners. The posts 31c and 32c should each have their teeth 33c arranged slightly toward the top, i. e. displaced 20° or 30° from the inner side position. The upper cover has a flexible or pivotal portion 34c located close to the perforations through which the fasteners pass, whereby a larger portion of a page is rendered visible when cover 24c is raised about its portion 34c as a pivotal axis. The top clamping plate may have the general shape indicated and be provided with notches or recesses 35 and 36 into which the side portions 11 of the fasteners can be swung past cam surfaces 37 corresponding to the rounded surfaces 26 in Figs. 7 and 8. It is because there may be no room at the sides of plate 30c that the recesses 35 and 36 may be provided on the top edge and just deep enough for the fasteners to be retained therein with a little locking effect. More than two separable fasteners and locking recesses therefor may be located along the upper edge portions of the covers and sheets enclosed therebetween. When not desired the recesses 35 and 36 can be omitted, but when used such recesses are also in the lower cover 25c, base plate 29c and also in the sheets of paper, clamped between covers. As was the case in Fig. 8 for example, the embodiment of Fig. 10 provides a construction having the advantages of both a post binder and a loose leaf binder, in being able to extract or insert pages anywhere desired quickly and easily and without having to remove a great many sheets from the binder. Having the pivotal portion 34c of the top cover 24c located close to the side portions 10 of the fasteners enables a large part of each sheet of paper to be made visible for writing and inspection. The clamping plates in each embodiment should be rigid and wear resisting material.

What is claimed is:

1. The combination with a pair of stiff covers between which perforate sheets are adapted to be held, a separable ring type fastener having a pair of substantially parallel and straight side portions, said covers being perforated adjacent at least one corner thereof, whereby said fastener may have one of its side portions extend through said perforation in each cover and the other side portion remain outside said covers and any sheets therebetween, the corner of said covers adjacent said perforation being rounded on a radius of curvature to enable the side of said fastener outside the covers to be swung through substantially a right angle, one edge of said covers being formed with aligned recesses into which the fastener may be sprung and from which the fastener may be removed by a flexure of said fastener to increase the separation of said side portions.

2. The combination with a pair of covers between which a plurality of sheets may be bound, said covers

having perforations adjacent a top edge thereof, ring type separable fasteners having parallel side portions with one of such side portions of each fastener passing through said covers and another and outer side portion of each fastener outside the covers, said covers each having a recess in an edge adjacent each fastener and into which a fastener may be swung with its outer side for reception therein, and a rounded camming surface over which such fastener side portion must be moved in moving it into and out of said recess, said surface being located at a distance from its adjacent cover perforation to cause the side portions of the fastener to be spread slightly in moving over such surface and into or out of said recess for holding said covers closed by said fasteners when received in said recesses.

3. The combination with a pair of covers between which a plurality of sheets may be bound, said covers having perforations adjacent a top edge thereof, ring type separable fasteners having parallel side portions with one of such side portions of each fastener passing through said covers and another and outer side portion of each fastener outside the covers, said covers each having a recess in an edge adjacent each fastener and into which a fastener may be swung with its outer side for reception therein, a rounded camming surface over which such fastener side portion must be moved in moving it into and out of said recess, said surface being located at a distance from its adjacent cover perforation to cause the side portions of the fastener to be spread slightly in moving over such surface and into or out of said recess, a pair of substantially rigid plates between which said covers and perforated sheets may be clamped, and a pair of upstanding posts secured to the lower one of said plates and spaced apart far enough to be outside said covers and outside any sheets between the covers, the upper plate being slideable over said posts and outside said ring type fasteners, said upper plate and posts being shaped for clamping engagement with said posts for different thicknesses of sheets therebetween, whereby said upper and lower plates may clamp at least one of the stack of sheets and covers with the posts under tension due to said clamping, said posts and plates being movable along said covers toward and from said fasteners and any sheets held by said ring type fasteners.
